SINK FRAME AND MOUNTING

William L. Bonnell, Youngstown, Ohio, assignor
to Trimedge, Incorporated, Youngstown, Ohio,
a corporation of Ohio

Application May 25, 1949, Serial No. 95,183

6 Claims. (Cl. 4—187)

1

This invention relates to sink frames and means for mounting sinks in connection therewith.

The principal object of the invention is the provision of a sink frame and means for mounting a sink in engagement therewith.

A further object of the invention is the provision of a sink mounting whereby a sink bowl may be mounted in a cabinet opening.

A still further object of the invention is the provision of a sink frame and mounting for sealing the sink with respect to the supporting structure thereof.

A still further object of the invention is the provision of a simple and inexpensive sink frame and mounting which may be easily installed and which is adaptable to various thicknesses of supporting structures as well as various types of sinks.

The sink frame and mounting comprises an improvement in the art of mounting sinks and more particularly sink bowls, counter and sink tops such as are customary in the art and wherein a water-tight seal is desired between the surface material of the supporting structure and the sink or sink bowl and whereby the sink bowl may be held in the supporting structure by the mounting means. The device disclosed herein comprises a sink frame which overlies the edge of the supporting structure as well as the edge of the sink or sink bowl and has means suspended therefrom for engaging both the supporting structure and the sink so as to hold the sink in desired position in relation to the supporting structure and the sink frame.

The device is therefore readily adaptable for use with various kinds and sizes of sinks and sink bowls positioned in openings formed in various supporting structures whether the same are of varying thicknesses of wood and including linoleum or tile tops or metal and either directly finished or provided with an auxiliary wearing surface. Most importantly, the sink frame and mounting disclosed herein provides a water-tight seal between the sink and a supporting structure and continually maintains the seal in compression so that the seal remains permanent throughout the life of the installation.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed.

2

without departing from the spirit of the invention.

The invention is illustrated in the accompanying drawing, wherein:

5 Figure 1 is a perspective view of a portion of a sink supporting structure and sink bowl installed therein.

Figure 2 is an enlarged horizontal section taken on line 2—2 of Figure 1.

10 Figure 3 is a perspective view of a portion of the sink frame and mounting shown in Figure 2.

By referring to the drawings and Figures 1 and 2 in particular it will be seen that a sink supporting structure including a top member 10 and a back wall member 11 are illustrated and provided with a surfacing material 12 such as linoleum and that the sink supporting structure and specifically the top 10 thereof has an opening 13 formed therein in which a flanged sink bowl 14 is located, the flange thereof being indicated by the numeral 15.

15 It will be observed that the opening 13 is larger than the over-all dimension of the flanged sink bowl 14. A sink frame 16 of general rectangular shape is positioned partially within the opening 13 in the top 10 and partially overlying the surfacing material 12 thereon. The sink frame 16 has a transversely convex contour in cross section extending from the outermost edge thereof which is bluntly pointed as at 18. The sink frame 16 also has a depending flange 19 formed thereon which is adapted to be positioned in the opening 13 and abutting the top 10 of the sink supporting structure as best shown in Figure 2 of the drawings. The sink frame 16 has a dovetailed channel 20 formed continuously therein in which the head of a bolt 21 is positioned, the head of the bolt 21 being of the same shape as the dovetailed channel 20 and slightly smaller so that it may be moved into desired position 20 in the frame 16 by sliding the same along the channel 20.

25 The majority of the bolt 21 is provided with a thread pattern 22 and a wing nut 23 is threadably engaged thereon. Prior to assembling the wing nut 23 to the bolt 22, a strap clamp 24 is engaged upon the bolt 22 by means of a slot 25 formed therein longitudinally thereof, as best shown in Figures 2 and 3 of the drawings. The strap clamp 24 is of modified arcuate shape, one end thereof forming a straight extension 26, the outermost end 27 of which is rounded as is the opposite end 28 of the arcuate strap clamp 24.

30 The sink frame and mounting and particularly the strap clamp 24 provides means for both holding the sink frame 16 downwardly so that the

35 strap clamp 24 is held in the slot 25 and the wing nut 23 is held on the bolt 22. The strap clamp 24 is held in the slot 25 by the head of the bolt 21 being received in the slot 25 and the outermost end 27 of the strap clamp 24 being received in the slot 25 so that the strap clamp 24 is held in the slot 25 and the wing nut 23 is held on the bolt 22.

40 The majority of the bolt 21 is provided with a thread pattern 22 and a wing nut 23 is threadably engaged thereon. Prior to assembling the wing nut 23 to the bolt 22, a strap clamp 24 is engaged upon the bolt 22 by means of a slot 25 formed therein longitudinally thereof, as best shown in Figures 2 and 3 of the drawings. The strap clamp 24 is of modified arcuate shape, one end thereof forming a straight extension 26, the outermost end 27 of which is rounded as is the opposite end 28 of the arcuate strap clamp 24. The sink frame and mounting and particularly the strap clamp 24 provides means for both holding the sink frame 16 downwardly so that the

flange 17 thereof tightly engages the surfacing material 12 on the top 10 of the sink supporting structure and supports the sink bowl 14 by engaging the flange 15 thereon, as shown in Figure 2 of the drawings.

It will be observed that due to the formation and arrangement of the mounting means, including the frame 16, the bolt 21 and the strap 24, the device is operative for its intended purpose regardless of the thickness of the top 10, the surfacing material 12, or both of them, and regardless of the thickness of the flange 15 of the sink bowl 14 as the strap clamp 24 will automatically assume the proper clamping position with respect to its bearing surfaces on the lower side of the top 10 and the flange 15 when the wing nut 23 is tightened thereagainst. It will be observed that the tightening of the nut 23 both positions the strap clamp 24 and holds the sink frame 16 downwardly. Thus the sink bowl 14 is both held in elevated relation in the opening 13 by the device and in engagement with the sink frame 16 which in turn is urged downwardly against the flange 15 of the sink bowl 14 by the same clamping action.

It will occur to those skilled in the art that the sink frame 16 may be advantageously formed as an extruded metal product which may be factory formed in accordance with the prevailing practice into the various sizes of frames to match the various sizes of flanged sink bowls so that the same construction is capable of use with any and all sizes of sink bowls in any and all types of supporting structures and regardless of the material or thicknesses of material thereof. In practice, the sink frame 16 is installed with waterproof cement beneath the flange 17 and beneath the frame 16 where it engages the surfacing material 12 and the flange 15, respectively, so that a water-tight seal under continual compression of the clamping device is realized.

It will thus be seen that the several objects of the invention are met by the sink frame and mounting disclosed herein.

Having thus described my invention, what I claim is:

1. Means for mounting a flanged sink in an opening in a supporting structure and comprising a frame of extruded metal of cross sectional T shape, the vertical section of which is adapted to be positioned between the edge of the opening in the supporting structure and the edge of the flanged sink and with the horizontal portion of said frame overlying the adjacent edges of the supporting structure and the flanged sink, the horizontal portion of said frame having a longitudinally extending dovetailed channel in the lower surface thereof adjacent said vertical section and a plurality of bolts, the heads of which are dovetailed to register with and are movably positioned in said dovetailed channel, a plurality of levers of extruded metal each of which is slotted longitudinally and each of which is engaged upon one of said bolts, and nuts threadably engaging said bolts for urging said levers upwardly against the lower surfaces of said supporting structure and the flanged sink whereby said flanged sink is moved into engagement with said frame.

2. Means for mounting a flanged sink in an opening in a supporting structure and comprising a frame of extruded metal of cross sectional T shape, the vertical section of which is adapted to be positioned between the edge of the opening in the supporting structure and the edge of the

flanged sink and with the horizontal portion of said frame overlying the adjacent edges of the supporting structure and the flanged sink, the horizontal portion of said frame having a longitudinally extending dovetailed channel in the lower surface thereof adjacent said vertical section and a plurality of bolts, the heads of which are dovetailed to register with and are movably positioned in said dovetailed channel, a plurality of levers of extruded metal each of which is slotted longitudinally and each of which is engaged upon one of said bolts transversely of said frame with its ends underlying said supporting structure and the edge of the flanged sink respectively, and nuts threadably engaging said bolts for urging said levers upwardly against the lower surfaces of said supporting structure and the flanged sink whereby said flanged sink is moved into engagement with said frame.

3. Means for supporting a flanged sink in an opening in a sink board, the opening being larger than the flanged sink, said means comprising a frame of extruded metal, the upper surface of which is convex in cross section and the lower surface of which includes two longitudinally extending transversely flat surfaces offset vertically with respect to one another and adapted to overlie the adjacent edges of the sink board and the flanged sink, the portion overlying the flanged sink being thicker in cross section and providing a feather edge with respect to the upper surface of the flange, a longitudinally extending dovetailed channel in said thickened portion of said frame and a plurality of vertically positioned bolts having dovetailed heads registering with and movably positioned in said dovetailed channel, a plurality of levers of extruded metal, each of which is slotted longitudinally inwardly from its ends and each of which is engaged upon one of said bolts transversely of said frame and with the ends thereof underlying said sink board and flanged sink, respectively, and nuts threadably engaging said bolts for urging said levers upwardly against the lower surface of said sink board and the flanged sink whereby said flanged sink is moved into engagement with the feather edge of said frame.

4. Means for mounting a flanged sink in an opening in a supporting structure and comprising a frame of extruded metal the upper surface of which is convex in cross section and the lower surface of which includes two longitudinally extending transversely flat surfaces offset vertically with respect to one another, the higher one of which is adapted to overlie the said supporting structure and the lower one of which is adapted to overlie the said sink, a depending flange on said frame and separating the said surfaces and adapted to locate the frame with respect to the edge of the supporting structure, a longitudinally extending continuous dovetailed channel formed in the lowermost surface of the frame inwardly from the edge thereof and a plurality of bolts having tapering heads slidably engaged in the said dovetailed channel and depending therefrom between the said sink and the said flange, apertured upwardly curving clamping members of extruded metal positioned on said bolts transversely of said frame and nuts on said bolts for urging the said clamping members upwardly so that their outermost ends engage the said supporting structure and the flanged sink, respectively.

5. Means for mounting a flat flanged type sink in an opening in a drain board comprising a frame of extruded metal of generally T-shaped

cross section which is adapted to be positioned with its vertical leg between the edge of the opening in the drain board and the edge of the flanged sink and with its horizontal section overlying the adjacent edges of the drain board and the flanged sink, the said frame having adjacent the vertical leg continuously extending fastener attaching formations and depending fasteners provided with attaching formations for engagement with the said frame, clamping members of extruded metal engageable on the said depending fasteners and means on the said fasteners for urging the said clamping members upwardly to engage the lower surfaces of the flat flange type sink and drain board adjacent thereto respectively.

6. Means for mounting a flat flanged type sink in an opening in a drain board comprising a frame which is adapted to be positioned with a portion thereof overlying the edge of the opening in the drain board and the edge of the flanged sink, means on said frame for locating the same between the adjacent edges of the opening in the drain board and said sink and means in the lower surface of the said frame for receiving fasteners, said means comprising a continuously extending dove-tailed slot, fasteners slidably positioned in

said dove-tailed slot at intervals therealong and depending between the said drain board and said flat flanged sink, apertured upwardly curving clamping members of extruded metal positioned on said fasteners transversely of said frame and nuts on said fasteners for urging the said clamping members upwardly so that their outermost ends engage the lower surface of the said drain board and flat flanged sink respectively and urge the said frame downwardly against the said flat flanged sink and drain board respectively.
